ROTARY PUMP

Julius Fuchs, Cleveland, Ohio, assignor of forty-five per cent to Augustus J. Baker, Cleveland, Ohio

Application November 12, 1943, Serial No. 510,050

2 Claims. (Cl. 103—136)

The present invention relates to a rotary pump of great simplicity and of high non-pulsating efficiency.

The invention also comprehends improvements in the specific construction and arrangement of parts which will be hereinafter described and particularly pointed out in the claims.

This invention relates to pump, compressor, and similar machines of the type employing rotating drums eccentrically mounted in the casing, the drums being provided with ways or vane slots in their peripheries in which radially disposed slidably mounted vanes or blades are carried.

The vanes or blades of each drum are maintained in frictional contact with the cylindrical walls in the casing by means of fixedly mounted shafts carried by the cover plate of the pump. The shafts are so positioned in the cover plate that they extend into the interior of the drums eccentrically, and each shaft is provided with anti-friction bearings.

A primary object of the present invention is the production of a pump of this type which is balanced mechanically, which is practically non-pulsating and in which the torque application closely approaches uniformity.

In the accompanying drawings in which similar reference numerals indicate the same parts throughout the several views,

Figure 1 is a view in elevation showing the interior of the pump and illustrating the manner in which the drums or rotors are mounted in the casing, and also showing in dotted lines the equal meshing gears mounted on the drum shafts.

Figure 2 is a view in elevation of the cover plate of the pump, and illustrating the manner in which the eccentrically positioned shafts are mounted in the cover plate and on which the roller bearings are rotatably mounted.

Figure 3 is a sectional view taken on line A—A in Figure 1.

Figure 4 is an end view on an enlarged scale of the rotor or drum showing the radial ways for the blades or vanes therein.

Figure 5 is a view on an enlarged scale showing the drum or rotor in the same position as that shown in Figure 3, and illustrating the position of the blades or vanes in their cooperative relation with the roller bearings mounted on the shaft in the cover plate.

Figure 6 is a view on an enlarged scale of the rotor or drum shown in Figure 3, and illustrating the position of the vanes or blades at right angles

to those shown in Figure 5 in their cooperative relation with the roller bearing mounted on the shaft in the cover plate.

Figure 7 is a detail view in elevation of one of the blades shown in the enlarged view in Figure 5.

Figure 8 is a detail view in elevation of one of the blades shown in the enlarged view in Figure 6.

Referring to the drawings the pump case is formed in two parts 10 and 11. In the part 10 there is provided two chambers 12 and 13 in which the drums or rotors 14 and 15 are eccentrically and rotatably mounted. In the drums there are provided radial ways 16 in which the blades or vanes slidably fit.

15 The part 10 is provided with an inlet opening 17 and an outlet opening 18. The inlet opening divides into two laterally disposed channels 19 and 20, which communicates with the chambers 12 and 13. The division is caused by the wall 21, which also extends upwardly between the rotors and terminates in the outlet opening as at 22 where it again divides the opening into two channels 23 and 24 through which the fluid is discharged into the outlet opening. The passage of the fluid through the pump is indicated by arrows.

Each rotor or drum is provided with a shaft that extends beyond the part 10 of the case. The shafts are rotatably journaled in a bearing as at 25, see Fig. 3. Each shaft is provided with a fixedly mounted gear as at 26 and 27. These meshing gears are equal each being provided with the same number of teeth. One of the shafts extends beyond the gear keyed thereon and is provided with a coupling as at 28, see Fig. 3, by means of which the pump may be connected to a suitable electric motor to actuate the pump. The teeth are not shown in Fig. 1 on the gears, but it is to be understood that the teeth are continuous around the periphery of each gear and are in meshing relationship.

In the part 11 or cover plate there are provided two fixed shafts 29 and 30 on which the roller bearings are mounted. One set of these roller bearings is shown at 31, 32 and 33 in Figs. 3, 5 and 6. The shaft is provided with a head 34 to prevent the bearings from slipping off the shaft, and a shouldered end as at 35 to connect the shaft to the cover plate. As both the shafts are the same, it is thought that the description of one will suffice for both. The parts 10 and 11 are held together by a number of bolts and nuts 36 and 37; the holes for the bolts are shown at 38.

One set of the blades or vanes is provided with

a profile or edge that is interrupted as at 39 so that portions of the blade rides upon two of the ball bearings as at 31 and 33, see Figs. 3, 5 and 6. The diametrically opposite blades or vanes are so formed that they are provided with a projection 40 that rides upon the ball bearing 32, see Figs. 3, 5 and 6. The blades are all notched at one end as at 41, to permit the blades to cooperate with the ball bearings mounted on the shafts in the cover plate. The vanes or blades are held in frictional contact with the chamber wall in their advancing or receding position by means of the shafts with their roller bearings thereon that are so arranged that they project into the interior of the drums eccentrically. It will be noted in Fig. 1 that the blades or vanes in the working chamber on the right as you look at the drawings are forty-five degrees from the vertical or horizontal, while the blades in the working chamber to the left are vertical and horizontal, and when assembled the gears are mounted on the shafts when the blades are thus positioned, because it has been found that the pump when so geared produces better results. The rotor drum in the working chamber to the right turns clockwise while the rotor drum in the working chamber to the left turns counterclockwise.

It is believed that the operation of the mechanism as a whole will be clear, in view of the foregoing description which has been given in connection with that of the construction of the same.

Of course, changes may be made in details of construction and arrangement of parts without departing from the spirit and scope of my invention. I do not limit myself, therefore, to the exact form herein shown and described other than by the appended claims.

What I claim as my invention and desire to secure by Letters Patent of the United States is:

1. A pump of the class described comprising a casing, a cover plate therefor, the casing having an inlet opening and an outlet opening, and also having a plurality of working chambers therein, a wall formation positioned in the casing its arrangement being such as to provide laterally disposed channels communicating with the working chambers therein from the inlet opening, and extending upward between the working chambers and forming a portion thereof but stopping short of the length of the outlet opening to provide discharge channels communicating with the outlet opening, rotor drums eccentrically mount-

ed in the working chambers, oppositely disposed vanes arranged radially in the rotor drums and slidably mounted therein, means mounted in and supported by the cover plate and projecting into the interior of the rotor drums eccentrically, a pair of the oppositely disposed vanes having an interrupted edge and adapted to ride upon spaced portions of the means projecting into the interior of the rotor drums, whilst the pair of vanes diametrically opposite are each provided with a projection that rides upon the portion between the spaced portions, the said projecting means adapted to effect frictional contact of the vanes with the wall in the working chambers, and means to actuate the rotor drums in unison.

2. A pump of the class described, comprising, in combination, a casing having an inlet and outlet opening and also having a plurality of working chambers therein, a wall formation in the casing its arrangement being such as to provide laterally disposed channels communicating with the working chambers from the inlet opening, and extending upward without interruption between the working chambers and forming a portion of the walls thereof but stopping short of the length of the outlet opening to provide discharge channels communicating with the outlet opening, rotary shafts, a rotor drum connected to each rotor shaft and formed with an end wall and having radial slots formed therethrough, eccentrically mounted in the working chambers, each rotor drum having a point of tangency with the working chambers symmetrically disposed at an angle of forty-five degrees to the vertical axis of the rotor drums to the right and left above the horizontal axis of the aforesaid rotor drums, a pair of vanes having a notched end and a notched edge oppositely slidably mounted in radial slots in the rotor drum, a second pair of vanes having a notched end and an edge having a projection thereon, oppositely slidably mounted in the other of the radial slots in the rotor drums, a cover plate for the casing, a headed shaft fixed in the cover plate, friction reducing means mounted on the fixed shafts and cooperating with the vane notches extending into the rotor drums eccentrically, the aforesaid friction reducing means adapted to maintain the vanes in frictional contact with the chamber walls on rotation of the rotor drums, and meshing gears connected to the rotor shafts to actuate the rotor drums in unison.

JULIUS FUCHS.
